UNITED STATES PATENT OFFICE.

LYNN G. RILEY AND HARRY R. MEYER, OF WILKINSBURG, PENNSYLVANIA, AS
SIGNORS TO WESTINGHOUSE ELECTRIC AND MANUFACTURING COMPANY, A COR-
PORATION OF PENNSYLVANIA.

TRAIN-LINE RECEPTACLE.

Application filed October 6, 1919. Serial No. 328,811.

To all whom it may concern:

Be it known that we, LYNN G. RILEY, a citizen of the United States, and a resident of Wilkinsburg, in the county of Allegheny and State of Pennsylvania, and HARRY R. MEYER, a citizen of the United States, and a resident of Wilkinsburg, in the county of Allegheny and State of Pennsylvania, have invented a new and useful

10 Improvement in Train-Line Receptacles, of which the following is a specification.

Our invention relates to connecting devices for multiple unit control circuits on electric railway cars and particularly to 15 train line receptacles for such control circuits.

One object of our invention is to provide means for permitting the insertion of the train line jumper in the receptacle only 20 in such position as will insure the proper connection of the control circuits from car to car.

Another object of our invention is to provide simple and easily operable locking 25 means for retaining the train line jumper in its operative position in the train line receptacle, which is mounted under the platform of the car.

Another object of our invention is to 30 provide means for holding said locking means in its locked position, thereby precluding accidental movement of the locking means and possible interruption of the control circuits.

35 In practicing our invention, we provide the usual receiving receptacle with a peripherally adjustable locking ring, which is, in turn, provided with two longitudinal slots in its inner periphery. Another lon-

40 gitudinally extending slot is provided in the outer periphery of the locking ring, to co-operate with a depending lug on one of the hinge members of the cover of the receptacle to retain the locking ring in its locking position. The jumper head casting

45 is provided with lugs or bosses co-operating with the slots in the inner periphery of the locking ring to permit the insertion of the jumper head only when the locking ring is 50 in a predetermined position.

In the two sheets of drawings, Figure 1 is a vertical sectional view of the device embodying our invention as used in connection with the receiving receptacle, with a

jumper head inserted in its operative position; Fig. 2 is a sectional view on the line II—II of Fig. 1; Fig. 3 is a front view of the locking ring; Fig. 4 is a top view, partially in section, along the line IV—IV of Fig. 3; Fig. 5 is a longitudinal sectional view along the line V—V of Fig. 3; Fig. 6 is a front view of the receiving receptacle, and Fig. 7 is a side view, partially in section, of the receptacle.

A receiving receptacle 1, substantially circular in contour is provided, at its rear end, with a cover member 2 suitably secured thereto, which cover member serves to protect the train line control wires 3, which are united in the form of a cable 4 and inserted in a conduit (not shown) under the body of the car. An insulating block 5 is located in the receptacle 1, and is provided with a suitable number of contact terminals 6 to which the ends of the wires 3 are connected. A screw plug 7 is provided in the cover member 2 to permit the space 8 in the cover to be filled with a suitable insulating material (not shown). The receptacle 1 is provided with a flange 9, which is, in turn, provided with a number of circular openings 10 to permit the receptacle to be secured to a part of the car platform. Two lugs 11 are provided to permit the mounting of the receptacle underneath the floor of the car platform if desired. Each of the lugs 11 has a projecting boss 12 that is provided with a circular opening 13 to receive a hinge pin 14, upon which pin is operatively mounted a flat cover member 15 having two hinge lugs 16 and 17. The lug 17 is substantially concentric with the hinge pin 14, but the lug 16 is of substantially cam shape eccentric to the hinge pin 14 as shown in Fig. 1. A coiled spring 15a is provided to bias the cover member 15 to its closed position. A plurality of radial bolts 18 are provided in the receptacle 1 for purposes hereinafter specified.

A circular locking ring 19, having a radially projecting arm 20, is provided with two longitudinal slots 21 and 22 in its inner surface, the slot 22 meeting and co-operating with a peripheral slot 23. A longitudinal slot 24 is provided in the outer periphery of the locking ring 19, the slots 21, 22, 23 and 24 having a definite spaced relation to each other. An end ring 25 is

suitably secured to one end of the ring 19, and co-operates with machined parts thereof to form an annular groove 26. A plurality of radial pins 27 are located in the 5 groove 26, being suitably secured to the ring 19. When the locking ring 19 is placed in its operative position in the receptacle 1, the inner ends of the bolts 18 project into the groove 26 and prevent longitudinal 10 movement of the ring relatively to the receptacle. The pins 27 co-operate with the bolts 18 to limit the peripheral movement of the locking ring 19.

Fig. 1 shows one jumper head of a jumper 15 cable, which comprises a hollow casing 28 substantially circular in contour and provided with two radial lugs 29 and 30 on the outer surface of the casing. A cable 31 comprising a plurality of individual conductor wires 32 is located in the casing 28, the conductors 32 terminating in suitable contact terminals 33 positioned in an insulating block 34 and co-operating with the contact terminals 6 to complete the control 20 circuits between two adjacent cars. An opening 35 is provided in the casing 28 to permit the pouring of insulating material in the space surrounding the end of the wires 32, to insulate them and to prevent 25 the entrance of moisture into the body of the cable 31, the opening 35 being closed by a screw plug (not shown).

Assuming that the jumper head is not in the receptacle 1 and that it is desired 30 to insert same and thus connect the control circuits, the locking ring will then be in such position in the receptacle 1 that the lug 20 will be in a vertically downward position, that is, it will be shifted in a clockwise direction from the position shown in 35 Fig. 3. The cover member 15 will be in a position to close the opening of the receptacle 1, and the depending portion of the hinge member 16 will be in the slot 24 and 40 lock the ring 19 in its position. The cover member 15 may first be raised, thus disengaging the hinge member 16 from the slot 24 and permitting the ring 19 to be moved in a counter-clockwise direction until 45 its movement is arrested by the engagement of two of the pins 27 with two of the co-operating bolts 18. When the ring is in this position, which is that shown in Fig. 3, the slots 21 and 22 will be in the position 50 shown, and the bottom surface of depending hinge 16 will rest upon the outer periphery of the upper part of the ring 19, adjacent to the slot 24, thus holding the cover member 15 in a substantially horizontal position.

The jumper head 28 may then be inserted in the receptacle 1, the lug 29 entering and passing through the slot 21, and the lug 30 entering and passing through the slot 22 55 and being positioned in the slot 23. The

ring 19 may then be moved in a clockwise direction until the lug 20 is in a vertically depending position and two of the pins 27 engage two of the co-operating bolts 18. When the locking ring is in this position, 70 the hinge member 16 will again engage the slot 24 and preclude a peripheral movement such as might be caused by the jolting and jarring of the car in operation.

By the use of the device embodying our 75 invention, we provide a positive means for preventing the insertion of the jumper head except in a predetermined position, which will insure proper connection of the control 80 circuits from one car to the other. The device prevents also the possibility of the jumper head being jarred out and interrupting the control circuits and makes possible the easy and quick insertion and removal of the jumper head. If the ring is not moved 85 to its locked position, the cover member will not close down to the position shown in Fig. 1 and the cover member therefore acts as a tell-tale to show whether or not the locking ring has been properly positioned 90 and locked.

While we have shown one embodiment of 95 our invention, various modifications may be made therein without departing from the spirit and scope of our invention, and we desire that only such limitations shall be imposed thereon as are imposed by the prior art or are specifically set forth in the appended claims.

We claim as our invention:

1. In a train line receptacle, the combination with a receiving member, a multiple-conductor terminal block located in said member, and a cover member for said receiving member, of means peripherally movable in said receiving member to restrain said cover member in a certain position.

2. In a train-line receptacle, the combination with a receiving member, a multiple-conductor terminal support in said member and a second multiple-terminal support, of a locking member supported by the receiving member, and a double bayonet-joint connection between the locking member and the said second terminal support, one longitudinal slot of the double bayonet joint being of greater depth than the other slot and the engaging lugs being so positioned longitudinally as to properly engage the slots when the two terminal supports occupy definite 110 relative positions.

3. In a train line receptacle, the combination with a receiving member, a multiple-conductor terminal block in said member and a cover member for said receiving member, of a second multiple-conductor terminal block, and means for permitting the insertion of said second terminal block in the receiving member only in a certain position 115 relatively to said first terminal block, and 120

100

means for interlocking said receiving and cover members.

4. In a train line receptacle, the combination with a receiving member, a multiple-conductor terminal block in said member and a cover member for said receiving member, of a second multiple-conductor terminal block, means dependent upon its position for permitting the insertion of said second terminal block only in a certain position relatively to said first terminal block, said means being peripherally movable to preclude the withdrawal of said second terminal block, and a connection between the cover member and the peripherally movable member whereby they are maintained in definite relative positions.

5. In a connecting device, the combination with a receptacle, a multiple-conductor terminal block located in said receptacle, a

cover member for said receptacle, a second receptacle adapted to operatively engage the first receptacle and a multiple conductor terminal block located in said second receptacle and adapted to co-operate with said first terminal block upon the engagement of said receptacles, of peripherally movable means in said first receptacle adapted to permit the insertion of said second receptacle in said first receptacle in one of its positions and to preclude the removal of said second receptacle in another of its positions, and means on said cover member for preventing movement of said peripherally adjustable means in one of its positions. 35

In testimony whereof, we have hereunto subscribed our names this 30th day of Sept., 1919.

LYNN G. RILEY.
HARRY R. MEYER.
